UNITED STATES PATENT OFFICE

2,668,363

MEANS FOR REGISTERING PRINTING PLATES

Stephen W. Lippitt, Lakewood, Ohio, assignor to
 The Cleveland Shopping News Company, Cleve-
 land, Ohio, a corporation of Ohio

Application August 1, 1950, Serial No. 176,941

5 Claims. (Cl. 33—184.5)

1

This invention relates to a system of insuring registration of printing plates made from matrices previously impressed to form a pattern for the plates to be cast against them, as in the usual stereotype process. The invention is concerned primarily with the operation by which the formed matrix or mat is tested for accuracy of the registration marks at the head and tail thereof, and then has its margins trimmed in accurate relation to the position of such registration marks.

By this system a number of mats may be successively trimmed in absolute uniformity, so that the printing plates made therefrom may be used successively for producing surmounting images in proper registration with each other, such registration being highly important, especially in color printing.

To the above ends, I have provided a method of mounting the mat, and a machine useful in carrying out the operation, wherein mats with improperly placed registration marks may be immediately discarded, after mounting and testing in the machine, and those with proper registration marks may have their margins trimmed without disturbing their tested position in the machine. Thus, successive mats, may all have identical edges with reference to their registration marks, so that the plates produced therefrom when clamped at their edges in similar positions on the printing rollers will have their matter in perfect registration.

My method, and a preferred form of machine for use in performing the method, is illustrated in the drawings hereof and hereinafter described in detail.

Briefly, the method comprises taking a mat, which has at least two registration marks at each end, and clamping it at one end on a movable carrier in such position that the marks at that end register with the cross hairs of positioned eye-pieces through which the marks may be observed. Then without changing the position of the eye-pieces, the carrier is moved until the marks at the other end of the mat are brought into the field of the eye pieces.

Now if the marks at the far end of the plate do not so register with the cross hairs of the eye-pieces or cannot be brought into such registration by a very slight skewing of the mat on the carrier, that mat is discarded as faulty, and the operation is repeated with another mat. On the other hand, when the registration marks at the far end do register with the positioned eye-pieces, it follows that the mat is perfectly marked, and it is then effectively clamped at the second end to the carrier.

2

After the properly positioned mat has been clamped on the carrier the next operation is to trim the margins of the mat. In the machine shown, the trimming of the longitudinal edges is effected by pressing cutters against the mat at its opposite margins while the carrier is moved in a path at right angles to the line connecting the marks at either end. Thus such longitudinal edges are trimmed in absolute parallelism and in a direction at right angles to the lines of the end marks.

Now one end of the mat is trimmed, by a traveling cutter which travels across it at a right angle to the path of the carrier. Then the other end 15 of the mat, while still on the carrier, is trimmed in parallelism with the first trimmed end.

At the completion of the trimming movements the completed mat is discharged from the carrier, and is in proper condition for mounting in the 20 stereotype casting device.

Successive mats for any series of imprints are mounted on the carrier with the eye-pieces in the position fixed according to the first mat, and are successively trimmed as described. The result is that all the mats of this series exactly 25 match each other with reference to their edges and registration marks. Such marks will be reproduced on the cast stereotype plates, and hence when such plates are clamped at their edges in the 30 printing machine and positioned with reference to their marks they will all accurately register with each other.

As stated, my invention includes the method above outlined and the apparatus illustrated in 35 the drawings, which will be shortly described in detail.

In the drawings, Fig. 1 is a perspective view of the machine as seen from the front; Fig. 2 is a perspective view of a mat before the trimming 40 operation; Fig. 3 is a perspective view of the mat showing the position it assumes when mounted upon the machine; Fig. 4 is an end view of the machine partly in section taken from the end indicated by the line 4—4 in Fig. 1; Fig. 5 is a vertical section taken on a plane indicated by the line 5—5 in Fig. 1; Fig. 6 is a top plan view of the portion of the machine as shown by the line 6—6 in Fig. 5; Fig. 7 is a section taken on a plane indicated by the line 7—7 in Fig. 6; Fig. 8 is an end 45 view partly in section of the drum and partly broken away illustrating the manner of attaching the mat on the drum; Fig. 9 is an end view partly in section illustrating the manner of completing the fastening of the mat on the drum; Fig. 10 is a plan view taken in the direction indicated by the line 10—10 of Fig. 9; Fig. 11 is a fragmentary end

view showing the detail of the locking or clamping mechanism and taken in the direction indicated by the line 11—11 in Fig. 10; Fig. 12 is a section taken on a plane indicated by the line 12—12 in Fig. 11; Fig. 13 is a fragmentary front elevation of the machine adjacent to the right hand end of Fig. 1; Fig. 14 is a section taken on a plane indicated by the line 14—14 in Fig. 13; Fig. 15 is a section taken on a plane indicated by the line 15—15 in Fig. 14; Fig. 16 is a top plan view of the right hand portion of the machine; Fig. 17 is a diagrammatic view illustrating the electric and pneumatic system for operating the cutter which trims the mat in a direction transversely thereof.

As appears more particularly in Figs. 1, 4 and 5 the frame of the machine shown comprises a hollow box-like standard 10 adjacent the right hand end and a vertical plate 11 at the left hand end, and suitable horizontal cross braces as the lower beam 12 and upper beam 13 and a cross rod 14. Rotatably mounted in the two standards 10 and 11 is a shaft 20 carrying between the standards a drum 30. The shaft 20, as shown in Fig. 14, extends into the hollow standard 10 and there carries a bevel gear 22 which meshes with a bevel gear 23 on a shaft 24 extending out of the front of the standard. On the forward end of this shaft 24 is a hand wheel 25 by which the shafts, gears and drum may be rotated manually.

The shaft 20 carries also within the hollow standard 10 an indexing wheel 26 having a pair of notches as 26a (Fig. 15), in its periphery, either of which may be engaged by a plunger 27 operated by hand lever 28 which is pressed by a spring 29 tending to maintain the plunger in a notch which registers therewith. By this means the drum is definitely locked in either of two positions and readily freed.

The drum 30, as shown, more particularly in Figs. 5, 8 and 9, is arcuate for only a portion of its periphery and on such arcuate portion carries arcuate shells 31 which are adjustable longitudinally of the drum. The shells are secured in adjusted position by radial screws 32, Fig. 5, which enter overhanging blocks 33 slidably mounted in undercut grooves in the drum body.

Slidably mounted in other undercut grooves in the body, adjacent the non-arcuate side of the drum, are bars 35 and 36 which carry the clamps as hereinafter explained. The bars 35 and 36 are shiftable longitudinally, to vary the position of the sets of clamps, by screws 37 rotatably mounted in one of the end members of the drum, as shown in Fig. 10 and threaded in clips 38 secured to the respective bars. Knurled knobs 39 on the outer ends of the screws enable them to be readily turned manually to shift the bar 35 or 36 in either direction.

The clamps 41 and 42 for opposite ends of the mat are secured to the bars 35 and 36. In use the clamps are normally held in definite position on the bars but they are so mounted that they may be shifted as desired relative to each other and to the bars. The clamps of each set comprise an anvil 43 having a foot entering a dovetailed slot in the respective bar 35 or 36. Screws 43a (Fig. 8) passing through the various anvil members and abutting the bottom of the dovetailed slot on the bar provide means for locking the clamp in any desired position to the bar.

Each anvil member 43 pivotally carries a clamping jaw 44 spring-pressed by a spring 45 so that it tends to lie in a normally clamping

position as shown in the instance of the lower clamp in Fig. 8.

There is one clamp for each registration mark on the mat. In Figs. 2 and 3, the mat A is provided at each end with a central registration mark *a* and side registration marks *a*¹, two of such side marks being shown at each end, though the system may be used with only one side mark at each end. Assuming there are three registration marks, as shown, then there would be three clamps at each end, as shown in Fig. 10.

The pivotal mounting of the movable jaws 44 of all of the clamps with the exception of the two central ones is effected by a pair of rods 46 and 47 longitudinally mounted in the drum. These rods are formed with keyways and the four extreme clamps shown have keys entering the keyways as indicated by the short radial pin 44a shown in Figs. 5 and 8. The rods 46 and 47 have rock arms 48 attached to an end of the rod, each arm carrying a spring-pressed plunger 49 adapted to engage a positioning notch in an end wall of the drum. The two central clamps are free on the rods; thus they may be operated independently, being readily opened by manual pressure on the projecting tail portions 44b of their movable jaws 44.

When the untrimmed mat is first placed on the drum it is clamped at opposite ends by the two central clamps only. Then the shifting of one or the other sets of clamps, by turning the respective screw knobs 39, causes the skewing of the mat as may be necessary to bring its register marks into proper registration with the eye-pieces about to be described. During this preliminary positioning of the mat, the four extreme clamps are held open by their respective rock arms 48 on the rods 46 and 47 and are thus idle, becoming effective only after the mat has been properly positioned, when they are released by the rock arms 48 and then serve to complete the clamping.

To insure the mat's lying snugly on the drum after the first central clamp has been applied, and as the drum is being turned by the hand wheel to bring the other end of the mat into position for the application of the second central clamp, I provide a pair of rollers 100 (Figs. 1 and 5) rotatable on a rod 101 carried by arms 102 extending from the frame rod 14 and preferably a second pair of rollers 105 carried by shorter arms 106 also mounted on the frame rod 14. All of these rollers bear lightly against the mat adjacent its edges.

The eye-pieces 50 through which the marks are observed are each carried by an arm 51 adjustably clamped on the stationary frame rod 14. As shown in Fig. 8, each arm loops around the frame rod, and is split at the far end and tightened on the rod by a clamping bolt 53. There are as many eye-pieces as there are registration marks at one end of the mat and the eye-pieces are longitudinally shifted as may be necessary to cause them to register accurately with the different register marks at the first-clamped end of the mat.

The eye-pieces may be of any approved form. As indicated in Figs. 6 and 7, each comprises a hollow barrel 54 clamped in the arm 51 by a set screw 55, this barrel carrying longitudinally spaced cross wires 56, between glass discs 57 and 58 at opposite ends of the barrel.

The means for effecting the longitudinal trimming of the positioned mat comprises a pair of rotary cutters 61 and 62, Fig. 1, mounted on re-

spective shafts journaled in tubular heads 63a on rock arms 63 which are mounted on a rock shaft 65. A foot treadle 66 is connected by a push rod 67 to a rock arm 68 (Figs. 4 and 5) on the shaft 65. This enables the cutters to be moved bodily into engagement with the opposite side margins of the mat on the drum, and the drum is then turned by the hand wheel to effect the cutting.

To rotate the cutter wheels 61 and 62, I provide belt pulleys, as 69, on the cutter shafts, each pulley being connected by an elastic belt 70 with a pulley 71 on a rotatably journaled driving shaft 72. This driving shaft carries a pulley 73 which is connected by a belt 74 to a driving motor 75, Fig. 4, supported by the standard 10. The two cutters are thus operated in unison when their motor is energized, as it may under control of a switch 77 on the standard 10, and the rotating cutters may be brought to active engagement with the mat whenever desired by the operation of the treadle 66. A counterweighted arm 65a (Fig. 4) projecting rearwardly from the rock shaft 65, while not sufficient to lift the cutters, is effective in reducing the force required on the treadle 66. Accordingly, the mere depression of the treadle 66 swings the two rotating cutters into engagement with the two longitudinal margins of the mat and trims them accurately in parallelism and at right angles to the roller axis.

The swinging movement of the cutter-carrying arms is comparatively slight and does not interfere with the driving action of the elastic belts 70. To steady the arms, I form their lower portions with arcuate slots 78 (Fig. 5) concentric of the shaft 65, the upper and lower edges of these slots occupying peripheral grooves in wheels 79 loose on the shaft 72.

The two cutters 61 and 62 are so located that their edges stand opposite grooves on the drum 40 either between adjacent spaced shells 31 thereon or between the endmost shells and the end plates of the drum member. Accordingly, the mat bridges across open grooves in the regions where the cutters engage it, and the cutters may thus pass entirely through the mat.

By reason of the various shells being longitudinally adjustable on the drum, the cutting regions may be spaced as desired to accommodate mats of different widths, and the cutters with their supporting arms and driving mechanism may be bodily shifted longitudinally as required to cause them to stand opposite grooves on the compound drum. For this purpose the cutter arms are merely keyed to the shaft 65 and clamped in set position and the driving pulleys 71 are shiftable on their shaft 72.

The transverse cutting of the ends of the mat is also effected while the mat is on the drum. This is by means of a rotary cutter 80 (Figs. 1 and 4) which may engage the mat in the region between the clamps and the adjacent edges of the shells. The cutter 80 is rotatably mounted in a sliding carriage 82. This carriage has a dovetailed base 83 slidable along a longitudinal guideway in the top frame bar 13. Mounted on the base 83 is a motor 85, the shaft 86 of which is coupled to a shaft 87 which is connected by gears 88 to the shaft 89 of the cutter 80. By this means the operation of the motor rotates the cutter.

The whole carriage with the motor, cutter and gearing is shifted longitudinally of the drum by a piston rod 90 carrying a piston in an air cylinder 91, supported by a bracket 15 projecting

laterally from the rear portion of the frame standard 10. See Figs. 13 and 16.

When compressed air is admitted to the cylinder the carriage with its rotating cutter is shifted so as to cause the cutter to cut off one end of the mat. The path of travel of the cutter being parallel with the drum axis, it follows that this cut-off end of the mat is absolutely at right angles to the sides which have been trimmed in

10 planes normal to the axis of the drum.

Following the operation of the end cutter, the same is retracted to normal idle position, then the drum is rotated by the hand wheel 25 to bring the other end of the mat into position aligning 15 with the cutter, and the cutter is then moved by the air cylinder over that end of the mat. This cuts off the mat at the final end at right angles to the sides, and the finished mat drops freely onto an inclined discharge chute 108, Fig. 4.

Any suitable means may be employed for controlling the air to the air cylinder. I find it convenient to provide a solenoid operated air valve indicated conventionally at 110 in Fig. 17, the same being supplied from a suitable electric source S and controlled by a switch, as shown at 111, on the front of the standard 10.

Recapitulating the operation of the machine shown, the mat is first placed on the drum when the drum is in the positioned indicated in Fig. 8 30 and the end of the mat is clamped by the central clamp of the 41 set, care being taken to bring the central mark directly at the point aligning with the crossing of the wires of the central eye-piece. Then the drum is turned, the 35 rollers 100 and 105 holding the mat snugly on the drum, until the other end of the mat comes into the position for engagement by the clamps of the 42 set and the central clamp of that set is applied to the mat.

After the mat has been clamped by the two central clamps, one or the other or both of the bars 35, 36 is shifted by the corresponding knob 39 until the side marks of the first end of the mat accurately register with the two corresponding eye-pieces. When this has been done at the first applied end of the mat, that end is effectively clamped by the application of the two extreme clamps at that end, operated by movement of the rock arm 48 on the shaft carrying those clamps. Then the drum is turned to test the position of the marks at the other end of the mat by the eye-pieces, which retain the same position they had when testing the first end. If in such test the marks at the second end show 55 inaccuracy of the marks, as occasionally happens, the mat is discarded forthwith. If the test shows the marks at the second end to be proper, the operator knows that the mat is accurately marked and is accurately positioned on the drum. He then applies the two extreme clamps at that end by the operation of the corresponding rock arm, and the mat is then ready for the trimming operation.

The cutters 61 and 62 are now applied while 65 rotating to the edges of the mat, by the depression of the treadle 66, and at the same time the mat is turned by the hand wheel, resulting in the two longitudinal edges of the mat being accurately trimmed. Then the drum is turned by the hand wheel as may be necessary to bring the end of the mat held by the clamps of the 42 set into position for transverse trimming, and such trimming effected. Then the drum is turned to feed the mat, freed at that end, partially onto the discharge chute 108 shown at Fig. 8, and,

when the other end is in position for transverse trimming the transverse cutter is again shifted, cutting off the final end of the mat, whereupon the finished mat slides down the chute 108.

It will be understood, from the disclosure in the drawings and the above description, that I have provided a machine in which a stereotype mat may be readily mounted and first tested for the accuracy of its register marks, and then if the marks are properly positioned on the mat the mat may be quickly and smoothly trimmed on all four margins in exact accordance with the positions indicated by the lines of register marks.

If the mat is found faulty on the eye-piece tests it is at once discarded; thus only those mats are delivered which are accurate throughout. Such accurate mat may be very readily mounted in the casting device with assurance that the stereotype plate will have its edges properly formed at right angles to each other and with its registration marks in proper relation thereto. Thus successive stereotype plates may be placed one after another in the printing press and operate to produce surmounting images in absolute registration.

I claim:

1. In an apparatus for testing stereotype mats, the combination of a rotary drum, means for clamping the ends of a mat extending about the drum, a pair of eye-pieces axially spaced along the drum and adapted to register with register marks at the ends of the mat, means for positioning the mat axially to align the marks at one end with the spaced eye-pieces, and means for turning the drum to bring the marks at the other end of the mat into the field of observation of the eye-pieces without changing the position of the eye-pieces to compare the position of the latter marks with the positions of the marks at said one end of the mat.

2. In a machine for testing stereotype mats, the combination of a mat carrier movably mounted in a fixed support, clamps on the carrier adapted to engage and hold opposite ends of the mat, a plurality of spaced eye-pieces adjustably mounted on the support adjacent the carrier for observing registration marks at either end of the mat according to the position of the carrier and adapted to be adjusted to align the eye-pieces respectively with the marks at one end of the mat, and other means for positioning the carrier to bring the marks at the other end of the mat into the adjusted field of the corresponding eye-pieces for comparing the position of the marks at the latter end of the mat with the position of the marks at the former end of the mat, each eye-piece comprising a hollow barrel having

two straight wires crossing each other and longitudinally spaced along the barrel.

3. In a machine for use with stereotype mats, the combination of a rotatable carrier adapted to support a mat about the axis of rotation, a pair of bars, means disposed parallel to the axis on the carrier body and slidably receiving the bars for longitudinal movement along the carrier, and clamps carried by said bars and adapted to engage the ends of a mat, said clamps having anvil members secured to the bars and movable jaws pivoted to the anvil members.

4. In a machine for use with stereotype mats, the combination of a drum, a hand wheel, gearing between the hand wheel and drum whereby the hand wheel may turn the drum, two sets of clamps, means movably supporting each set of clamps in circumferentially spaced relation for independent axial adjustment on the drum, each set of clamps adapted to engage opposite ends of a mat extending about the drum and including a freely operable clamp and a clamp coupled with mechanism adapted to hold it in open position.

5. In a machine for testing the position of register marks on stereotype mats, the combination of a rotary drum, a pair of circumferentially spaced clamps axially centered and mounted on the drum and adapted to engage opposite ends of a mat extending about the drum, rollers bearing against the surface of the mat to maintain it smooth as the drum is turned, and eye-pieces spaced from each other along the drum axis and adapted to observe the position of the register marks on each end of the mat for comparison of their registration with each other and the eye-pieces.

STEPHEN W. LIPPITT.
